UNITED STATES PATENT OFFICE.

JAMES C. LAW, OF SCRANTON, PENNSYLVANIA.

SEPARABLE-LINK CHAIN.

Application filed October 4, 1921. Serial No. 505,368.

To all whom it may concern:

Be it known that I, JAMES C. LAW, a citizen of the United States, residing at Scranton, in the county of Lackawanna and 5 State of Pennsylvania, have invented certain new and useful Improvements in Separable-Link Chains, of which the following is a specification.

This invention has reference to separable link chains of the bar type, wherein separation is effected by removal of a bolt, pin, or like device, in contradistinction to those which may be separated upon moving connected links to abnormal position. 10 The objects sought are: To produce a chain suitable for use in carriers, conveyors, scrapers, and similar structures, and as drive chains, which shall be simple in construction and of great strength for given weight of material, and which shall have 15 large bearing surfaces at all points subject to wear, so that the chain may be durable, and efficient in action. Other features will be noted in the course of the following description.

With these objects in view a construction has been devised wherein each link or bar carries at one end a box or coupler, preferably of D-form or having a semicircular or 20 arcuate flange or wall forming a seat or bearing for a similarly shaped head of the companion link, the box or coupler being completed by a second section or cover, secured to the first by a bolt, pin, or like fastening or fastenings. One section of the box or coupler may be made integral with the bar or link, or suitably attached thereto, while the other or cover section is readily 25 detachable from the first to permit the semicircular head of the companion link to be withdrawn from the box-like coupler when necessary.

The preferred construction is illustrated in the accompanying drawings, wherein:

45 Fig. 1 is a perspective view of a short section of chain embodying my invention;

Fig. 2 a similar view, with parts separated to show the details of construction;

Fig. 3 a side elevation of one of the chain

joints with the cover section of the connecting box or coupler removed, a flight-bracket or carrier being also shown in position;

Fig. 4 a perspective view of two links or bars and an intermediate box or coupler, with two flight-brackets or carriers in place 55 thereon, as viewed from the front or advancing face;

Fig. 5 a similar view, looking from the rear;

Fig. 6 a perspective view of one of the 60 flight brackets detached;

Fig. 7 a perspective view of an insertable wearing strip.

As best seen in Figs. 1 and 2, the chain is made up of straight bars 1, preferably, 65 though not necessarily of rectangular cross section, each provided at one end with a heavy head or enlargement 2 of substantially semicircular form, and of a width or measurement at a right angle to the thickness of 70 the bar, considerably greater than such thickness, so that it projects beyond both side faces of the bar. 3 indicates a box-like coupler of substantially D-form in outline, and having on one side face a projecting 75 flange or overhang 4 of considerable thickness, conforming to the contour of the member 3. The side wall and flange together produce a box or housing, which is completed by a substantially duplicate cover 80 member 5.

The flange or overhang 4 of each member 3 is advisably provided with a notch or seat 6 (one or more), to receive a corresponding lug or projection 7 of the companion or 85 cover member 5, to aid in retaining the two parts in proper relation when united by a bolt 8, a pin, or the like, which passes through the two members and is suitably secured against withdrawal. In the drawings 90 I have shown a bolt, 8, which is headed at one end to bear against the outer face of one member, and is threaded at the other end to receive a nut 9 which bears against the outer face of the other member, and serves 95 to press and hold the two firmly together. A cotter pin 10 may be used in lieu of or in addition to the nut if desired. Such pin

is shown in Fig. 1 outside the nut 9, where it will prevent the nut from unscrewing or working off. If used without the nut, it will of course be located close to the wall of the box or head 3, with a washer 22 between.

To afford clear space for the pin or bolt 8, the head 2 is made of arcuate form, or with a recess 11 coaxial with the semicircular bearing face of head 2, and preferably of 10 larger radius than the pin or bolt 8, so that it shall not bear normally on said pin or bolt. Said pin or bolt is thus relieved of any stress or wear incident to the movements of or to the stresses brought upon the links 15 or bars 1.

To afford adequate movement of the bar 1 and head 2 relatively to the coupler 3-5, the overhang of both members 3 and 5 of the coupler is cut away between the points 12 20 and 13 (Figs. 2 and 3), to a depth equal to one half the thickness of bar or link 1, or slightly more, so that a relative movement of the bar or link and coupler may take place about the axis of the curved portion of 25 flange 4 and head 2, which in the embodiment illustrated would be coincident with the axis of pin or bolt 8. The opposite end of each bar or link, that is to say, the end remote from the arcuate head 2, may be 30 made integral with the box-like coupler member 3, or as is preferred, may be provided with a T-head 14 projecting past the side faces and upper and lower edges of the bar 1, as plainly shown in Figs. 2 and 3. 35 For convenience and cheapness of construction it is preferred to make the member 3 of the coupler separate and distinct from the link, as of course the cover section 5 will be in any event.

40 The head 14 is of the form shown in Figs. 2 and 3, the face opposed to the head 2 of the companion link being beveled on lines substantially radial to the axis of movement of said head 2, so that one or the other 45 of the radial faces of the head 2 shall, when the maximum relative movement of the link and coupler occurs, lie substantially parallel with one or the other beveled face of the head 14, and if desired may make contact 50 therewith thus limiting the relative play of the coupler and link. This limitation may, however, be effected by the walls 12 and 13 which form the upper and lower limits of the cut-away portion of the flanges or overhangs 4 of the coupler members. To permit 55 the introduction of the T-head 14 of the link or bar into the coupler 3-5, the straight wall of each member of the coupler is provided with a recess 15, seen in Figs. 1, 2, 3 and 4, of a size to receive and somewhat closely fit the bar or link 1.

A succession of links or bars and intermediate couplers being connected in the manner indicated and made secure by the pins or

65 bolts 8, the chain is adapted for use as a simple driving chain. To adapt it for use as a carrier, conveyor, scraper, elevator, or the like, I provide it with brackets or supporting plates 16, one form of which is shown 70 in Figs. 3, 4, 5 and 6. These plates or bracket members may be varied in form and dimensions as required by the particular service for which the chain is intended, and brackets of different form may be interchangeably employed and applied to the 75 chain. Each bracket will comprise a plate or cheek piece 7 conforming more or less closely to the contour of the outer face of the coupler members 3-5, provided with a hole 18, with a rib 19 to bear or rest upon 80 the upper face of the coupler members 3-5 with the parts in the position shown, and with a lug or foot-piece 20 to bear against the straight front face of the coupler and to rest upon the upper face of the link or bar 85 1, as indicated in Figs. 3, 4 and 5. The brackets will be provided with wings 21 of such form and dimensions as best suited to the part to be attached to or carried by them. The brackets are applied to the side faces of 90 the coupler and are held in place by the bolt 8, which passes through them as well as through the coupler proper. The brackets illustrated in the drawing are designed more particularly for carrying boards, flights or 95 scrapers, either on a single chain or a plurality of chains arranged parallel one to another, the wings 21 being shown with perforations to receive bolts by which to fasten such braces or flights to them. Where two 100 or more chains are arranged parallel to each other and driven by sprocket wheels in like number, the boards, flights, or like attachments will be fastened to the brackets of the several chains; in other words, will extend 105 from chain to chain transversely to the line of travel thereof. The usual conveyor buckets and similar attachments of common form may be carried in the well-known manner, upon bars, rods or other supports extending 110 between the brackets of the respective chains. The bolts 8 may likewise be used to carry attachments of any usual type.

115 By the construction above described, in which only one end of each link has play or movement relatively to the coupler, the cost of fitting and finishing the rubbing or wearing surfaces of a chain is materially lessened as compared with a construction in which both links have such play, and since play 120 adequate to a proper bending of the chain to pass about the sprockets is provided under the construction shown, it will obviously function as well as a chain in which both links have movement within or relatively to 125 the coupler.

Owing to the large wearing surfaces the wear will be quite slow, but such as may oc-

cur may be readily compensated for by introducing into each of the members of the coupler a steel wearing strip 23, which may be sprung or bent to the form shown in Fig.

5 7 and thus made to retain its position therein, passing from the upper end of the straight inner wall around the curved portion thereof, and finally to the lower end of said straight wall, as indicated in Fig. 3.

10 The parts may be made of any suitable material, and by any usual process or method. Thus the links or bars, coupler sections, and brackets may be cast either of malleable iron or of steel, or may be drop forged, 15 or produced in any ordinary way.

It will be noted that the flange or overhang 4 of the head 2 may be made as heavy as desired, thus affording great strength in the hinging portion of the structure, and that 20 large wearing surfaces are provided throughout, not only within the coupler box but on the outer faces thereof, which afford contact surfaces for engagement with double-flanged sprocket wheel teeth, used to 25 impart motion to the chain, and while the assembled construction of this chain indicates the chain being so driven, it is obvious that the chain may also be driven by either a single-toothed flanged sprocket 30 wheel (as a single drive), or in like manner, if the chain is operated as a double-strand conveyer or elevator, so that I do not wish to be limited to the employment of only double-flanged sprockets.

35 It will be noted that the bearings, being completely housed when the chain is normally operating, permit the lubricant to be held within the couplers 3, and an oil hole may therefore be provided as at 24, Figs. 1 40 and 2, for introduction of lubricant, or which lubricant may be inserted through the bolt-hole in the coupler, either before the bolt 3 is inserted and locked, or upon withdrawing such bolt to the extent of allowing insertion of lubricant into the box-like chamber, without entirely disconnecting the joints.

One of the outstanding advantages of this chain is that, after ordinarily being worn 50 out for service, the bearings may be quickly and cheaply renewed by insertion within the box-like members or couplers 3, of the bushings or wearing strips 23, Fig. 7, of proper thickness to fully restore the chain to normal chain pitch, and to so render the chain serviceable for fully fifty per cent additional life. A single bar chain of this type also precludes the possibility of carrying foreign material of an obstructive character 55 to the head sprocket, to cause the chain or sprocket teeth to break, as not infrequently happens when chain of the two and one-bar type is used.

It will be seen from the foregoing that the

chain constructed as described attains the 65 several objects stated in the specifications.

Having thus described my invention what I claim is:

1. A chain comprising a series of bar links each provided at one end with an arcuate 70 head and at the opposite end with a T-head, both integral with the link; and intermediate couplers comprising two hollow D-shaped sections each having an overhanging flange on one face cut away to receive the 75 bar links, and a fastening member passing through the two coupler sections and serving to bind them together.

2. A chain comprising a plurality of bar links, each having at one end a flanged arcuate box-like member incapable of movement relatively to the link, and at the other end an integral head of arcuate form, of radius substantially the same as the inner wall of the box-like member and seated in such member of an adjoining link; a cover member of like form matching the first box-like member; and a bolt passing through the two box-like members and serving to bind the same together.

3. A chain comprising bar links 1 each provided with a T-head 14 and an arcuate head 2 both integral with the link; and a coupler for the proximate ends of each pair of links, consisting of two matching box-like sections of arcuate form, the matching walls of which are recessed or cut away to receive the bar links and to permit a swinging or oscillating movement of but one of said links.

4. In combination with a plurality of bar links 1 each provided at one end with an arcuate head 2 and at the opposite end with a T-head 14 each integral with the link; a coupler comprising two box-like members each provided with an arcuate flange or overhang 4 cut away to permit the introduction of the bar links between the coupler members and allow play of one of said links, the coupler members being provided respectively with a notch and a projection to enter said notch to maintain them in proper relation; and a fastening 8 passing through both members of the coupler and serving to bind them together.

5. In combination with bar links each having at one end an arcuate head and at the opposite end a box-like coupling head of similar arcuate form in which the arcuate head of an adjoining link is seated; a cover member for the box-like coupling and corresponding therewith in form; a fastening extending through the coupling members and serving to bind the two together; and replaceable wearing strips seated in the coupler on opposite sides of the bar links between the arcuate head and its seat, and bearing at their ends against the straight

wall of the coupler, substantially as shown, whereby they are prevented from shifting their position when the chain is in use.

6. In combination with a chain comprising bar links and an intermediate box-like coupler, a bracket member comprising a plate corresponding in form to the side face of the coupler member, and provided with projections to engage the top and front face

of the coupler and with a hole corresponding to the bolt hole of the coupler; and a bolt or fastening passing through said bracket plate and the coupler and serving to secure the former to the latter.

In testimony whereof I have signed my name to this specification.

JAMES C. LAW.
